BINDER

Herman T. Arends, Highland Park, Mich.

Application November 29, 1933, Serial No. 700,202

6 Claims. (Cl. 281—19)

This invention relates to binders for ledger sheets, books, magazines, catalogues, and in fact sheet material of virtually any sort of substantially uniform size, at least in one dimension. An important object of the invention is the provision of a binder of simple and inexpensive construction adapted to very firmly hold papers or pamphlets bound therein in permanent or semi-permanent form yet without tightly clamping the sheets together at their bound edge, and so designed that the binding of material therein may be very quickly and easily done, without the use of tools, and that the bound material may be removed with equal ease when desired.

A further object resides in the improvement of the constructions disclosed in my previously issued patents, Nos. 1,688,514; 1,791,784; 1,825,257; issued Oct. 23, 1928; Feb. 10, 1931; and Sept. 29, 1931, respectively.

Other objects and advantages will be apparent from the following description wherein reference is made to the accompanying drawings illustrating preferred embodiments of my invention, and wherein similar reference numerals designate similar parts throughout the several views.

In the drawings:

Fig. 1 is a perspective view showing in vertical section a portion of a binder incorporating the principles of this invention, a quantity of material bound therein also being shown and the cover removed.

Fig. 2 is a plan view showing the top of the binder, and, fragmentarily, the material bound therein.

Fig. 3 is a fragmentary perspective view of the binder fully opened and empty.

Fig. 4 is a perspective view of portions of a pair of the retaining members, showing the same spaced from each other but preparatory to being interfitted.

Fig. 5 is a view similar to Fig. 3 of a somewhat modified form of the invention, showing certain parts removed and spaced from the rest; and

Fig. 6 is a view similar to Fig. 4 of equivalent portions of the modified binder.

In the drawings, the cover boards of my improved binder are designated 10 and may be of any suitable construction. They are each hinged along one edge to a substantially flat back portion 12 in the conventional or any desired manner, as by means of the covering material 11. The back is adapted to support the holding elements for the bound material. In the form

shown in Figs. 1 to 4 inclusive the holding means includes a limp supporting member 14, which may be formed of cloth or leather, extending across the inside of the back portion 12, and secured in any suitable fashion, as by gluing. Its ends may project partly across and be secured to the cover boards 10, being shown trucked beneath the inner finishing cover 16 to strengthen its support and the hinging connections between the sides and back. Adjacent each hinged corner 10 of the covers and back the material of which the member 14 is formed is folded to form elongated tubular securing loops 15 extending along substantially the entire length of the back.

The tubular securing loops are adapted to receive sheet metal fastening strips 17, which are preferably formed of soft and easily bent metal, such as thin brass. The strips 17 will be seen to be so arranged that when the covers are closed they lie substantially parallel thereto and serve as abutments between which the bound material may be confined at its bound edge.

The retaining assemblies for the bound material are arranged one at each end of the back and attached to the cover by means of the strips 17. Each may comprise a pair of telescopingly interfitting sheet metal members 19—20, lying flat against the back and each provided with an integrally inwardly bent portion 21—22 respectively adapted to fit into slots in the bound material 30 to lock the same in the binder. Also integrally formed at the ends of the locking portions 21—22 are looped strip portions 23—24 forming sideways adapted to slidably receive the strips 17. Elements 19—20 of the retainer assemblies are additionally held in slidably interfitting relation by the overbent inner edge portion 25 of the outer member 20, which, cooperating with the overbent outer portion 22 serves to slidably confine the member 19.

It will thus be seen that members 19—20 are capable of limited expansive and contractive movement to somewhat change the capacity of the binder, and that they may also be moved toward and away from each other when the strip portions 17 are straight, or held against such separating movement by simply bending over the ends of strips 17 in the manner indicated at 17' in Fig. 3.

The bound material, shown in Figs. 1 and 2 and designated 30, is initially provided across its top and bottom, near the back edge, with a transverse slot, designated 31, into which the portions 21—22 of the retaining members 19—20 are adapted to fit when forced thereinto by pushing the

members together as far as the material will permit, in the manner indicated in Fig. 1. In this locked position they may be held and the bound material thus tightly secured by bending over 5 the strip 17 as above noted, while by simply straightening the strip and separating one of the retaining assemblies from the other, the material may be quickly removed, as will be readily apparent.

10 In the modified construction shown in Figs. 5 and 6 like reference characters have been applied to equivalent portions, with the addition of the distinguishing figure "a". The member 14a may be constructed and positioned similarly to the 15 member 14 of the embodiment first described, although the inwardly projecting folded portions 15 thereof need not be separable to adapt them to receive devices within them, since the strips 17 are dispensed with in this construction. The 20 retaining members 19a—20a are each provided with overbent end portions 21a and 22a adapted to enter the slots in the bound material in an analogous manner, and from the tops of the overbent sections project elongated securing portions 25 35 adapted to be bent down over the outside of the members 15 when the material to be bound has been inserted in the binder and secured in place by forcing the retaining members together and their overlapped portions 21—22a into the 30 slots in such material. To prevent separation of the retaining assemblies the portions 35 are secured to the members 15, and to the bound material in addition if desired, by means of tacks 37, driven through the ends of the strips 35 and 35 portions 15 and into the bound material. It will be seen that when the covers are closed the tacks are locked against removal, while they positively prevent endwise movement of the retaining assemblies away from each other at all times, as 40 a result of which the retaining members function similarly to those of the first embodiment to lock the bound material securely in the binder, while if it is desired to remove any of the bound material, it is simply necessary to pull out one pair 45 of tacks 37 and separate one retaining assembly from the other, after which reinsertion or replacement of material may be made by a simple reverse operation.

While it will be apparent that the illustrated 50 embodiments of my invention herein disclosed are well calculated to adequately fulfill the objects and advantages primarily set forth, it is to be understood that the invention is subject to variation, modification and change within the 55 spirit and scope of the subjoined claims.

What I claim is:

1. In a binder for sheet material, a cover having swingable side panels and a substantially flat back portion, a pair of holding assemblies for the 60 material to be bound, said holding assemblies being carried by and near opposite ends of the back portion and each comprising interfitted sheet metal members slidably relatively to each other laterally of the back, an overbent portion carried 65 by the outer member of each of said assemblies and bent back over but spaced from the other member, the overbent portions of said assemblies projecting toward each other and longitudinally of the back, means releasably securing 70 said assemblies together and to the back and against movement away from each other, comprising manually deformable metallic strap elements adapted to be overbent with respect to a portion of each such assembly, and means se- 75 curing the straps to the back.

2. In a binder for sheet material, a cover having swingable side panels and a substantially flat back, holding means for the material to be bound, including portions slidably interfitted for movement toward and from each other laterally of the back, means releasably securing such portions to the back, means carried by said portions for securing the bound material to the binder, comprising inwardly projecting locking portions carried by said portions and appurtenant opposite ends of and spaced from the back, each of said locking portions projecting toward the end opposite to that to which it is appurtenant for engagement with irregularities carried by the top and bottom edges of the material to be bound, and means releasably securing at least one of said assemblies comprising such slidably interfitted portions away from the other including a deformable elongated metallic binding element adapted to be bent over a portion thereof. 10 15 20

3. A binder for sheet material including a cover comprising swingable side panels and a substantially flat back portion, means arranged within the back for securing the material to be bound in the binder including opposed pairs of slidably interfitting sheet metal members arranged near each end of the back, the members of each pair being movable toward and from each other laterally of the back, a locking portion carried by a member of each pair and projecting toward the 30 opposite end of the back for engagement with the material to be bound, and elongated deformable securing means connecting and releasably securing said opposed pairs to the back and against movement away from each other. 35

4. In a binder for sheet material, a cover comprising swingable side panels and a substantially flat back portion, means for securing the material to be bound within the binder including opposed pairs of slidably interfitting sheet metal members, one pair arranged near each end of the back, the members of each pair being movable toward and from each other laterally of the back, a locking portion carried by a member of each pair and spaced from the back and projecting toward the 40 opposite end of the back for engagement with the material to be bound, securing portions projecting inwardly from the back in substantial parallelism to the covers when the latter are parallel, and means for securing said opposed 45 pairs to the securing portions, releasable holding means for maintaining at least one of said pairs against movement away from the other and in desired position with relation to the back.

5. In a binder for sheet material, a cover comprising swingable side panels and a substantially flat back portion, means for fastening the material to be bound within the binder including opposed pairs of slidably interfitting sheet metal members, one pair arranged near each end of the 60 back, the members of each pair being movable toward and from each other laterally of the back, a locking portion carried by a member of each pair and spaced from the back and projecting toward the opposite end of the back for engagement with the material to be bound, securing loops carried by the cover and extending longitudinally of the back, and deformable fastening elements extending through the securing loops and attached to said pairs of fastening members. 65 70

6. In a binder for sheet material, a cover having swingable side panels and a substantially flat back portion, holding means for the material to be bound including portions slidably interfitted for movement toward and from each other later- 75

erally of the back, opposite and inwardly projecting locking portions carried by said slidably interfitting portions appurtenant opposite ends of the back for engagement with irregularities carried by the edges of material to be found to secure the same in the binder, means securing at

least one of such portions to the back and against movement away from the others, comprising a manually deformable attenuated metallic binding element.

HERMAN T. ARENDs.
